DESIGN FOR A CONNECTING STRIP FOR SUSPENDER STRAPS

Hyman Epstein, New York, N. Y.

Application July 18, 1939, Serial No. 86,065

Term of patent 7 years

To all whom it may concern:

Be it known that I, Hyman Epstein, a citizen of the United States, and resident of New York city, in the county of New York and State of New York, have invented a new, original, and ornamental Design for a Connecting Strip for Suspender Straps, of which the following is a specification, reference being had to the accompanying drawing, forming a part thereof.

Fig. 1 is a perspective view of a connecting strip for suspender straps, showing my new design.

Fig. 2 is a bottom edge view of the same.

I claim:

The ornamental design for a connecting strip for suspender straps, as shown.

HYMAN EPSTEIN.
